POCKET CIGARETTE MACHINE

Ernest Hansen, Greenwich, Conn.

Application July 6, 1937, Serial No. 152,219

7 Claims. (Cl. 131—5)

This invention relates to an improved portable apparatus for manufacturing cigarettes and more particularly to an apparatus of this type adapted to be conveniently carried in the pocket.

Heretofore, portable devices for manufacturing cigarettes have not found great favor largely because restrictions in size, as well as other considerations, have not permitted incorporation in these devices of means for adapting same to different types of tobacco commonly used in cigarette manufacture. To be satisfactory, a device of this nature should be easily alterable, preferably by variation in the compression exerted during rolling of the cigarette, whereby both cube and long cut tobacco, as well as tobaccos of different moisture contents can be readily and practically used.

It is an important feature of the device according to the present invention that means are provided whereby the compressive forces utilized during rolling of the cigarette can be freely and materially altered, thereby permitting the operator to vary the firmness or degree of packing of the tobacco within the paper, whereby tobaccos of highly dissimilar characteristics can be feasibly utilized.

Another feature of the present invention lies in its simplicity whereby the desired results are accomplished with the minimum number of moving elements. Furthermore, because of the arrangement of its members, it is easily freed from dirt and bits of tobacco which normally accumulate during operation.

A further feature is that the cigarettes manufactured by means of the device prepared according to the present invention have turned-in end papers whereby discharge of loose or short tobacco fibres into the mouth of the user is minimized.

In one embodiment of the device according to the present invention, provision is made for the storage of cigarette papers and, if desired, of cigarettes, thereby making the device of even greater value to the user.

The invention will be fully and comprehensively understood from a consideration of the following detailed description when read in connection with the accompanying drawings which form part of the application.

In the drawings:

Fig. 1 is a perspective view of a cigarette manufactured by means of the device according to the present invention.

Fig. 2 is a perspective view of the device according to the present invention.

Fig. 3 is a vertical sectional view of the device and illustrating the initial step of preparing a cigarette.

Fig. 4 is a sectional view of Fig. 3 taken along the line 4—4.

Fig. 5 is a sectional view of Fig. 3 taken along the line 5—5 of Fig. 7.

Fig. 6 is a vertical sectional view similar to Fig. 3 and representing the device during the making of a cigarette, said cigarette being partially completed; and Fig. 7 is a cross sectional view of Fig. 5 being taken on a plane perpendicular to the axis of the cigarette in Fig. 5.

Referring to the drawings, the device comprises a base member 10 having an undulated upper 15 surface formed by a plurality of grooves disposed therein substantially as shown, and a flexible apron or mat 11, equal in width to the width of the undulated portion of the base, which is permanently positioned in a recess 12 in the block 10 20 between certain of the undulations thereof substantially as shown. The apron 11, which normally rests upon the tops of the ridges in the undulated surface, is preferably adhesively attached over the entire front and rear area of the 25 upright element 13, whereby a substantially unitary construction is formed which is removably mounted by means of tongue and recess upon a projection 14 of the base 10, the other end of said apron being fixedly mounted as aforesaid. 30 The upright element 13 is preferably formed of relatively hard material so that its shape will not be substantially altered in use. Altho a form such as that illustrated is preferred other shapes can be used but it is desirable that the face 13a 35 thereof present a substantially flat surface. The apron 11 in the preferred embodiment of the present invention is made of surfaced rubber or rubber-like material having a facing not readily affected by tobacco particles and to which tobacco particles will not normally adhere. Altho other substances can be used to replace rubber, for example, parchment, surfaced fabrics and the like, experience indicates that rubber is preferable for this purpose. The upright members 15 are 40 fixedly positioned in abutting relationship to the undulated base member 10 and are provided, toward the top thereof, with recesses generally designated as 16 which extend thruout their entire length. The cover 17, which is preferably attached to the base member 10 by the hinge elements generally designated as 18, is adapted to fit snugly over the ends of the said upright members 15 and so to provide a substantially sealed closure for the apparatus.

When the cover 17 is closed the member 13 is not positioned upon the projection 14 of the block 10 as shown in Fig. 3, but instead is horizontally disposed upon the ridges of the member 10. In 5 operation the supporting member 13 is positioned substantially as shown in Fig. 3 upon the projection 14 of the base member 10. When so disposed the apron 11 is disposed substantially as shown. A cigarette paper generally designated as 20, the thickness of which is exaggerated for 10 the purposes of illustration in the drawings, is then positioned within the recesses 16 of the blocks 15 so that one end thereof is in the vicinity of the bend in the apron generally designated at 15 11a. The tobacco to be used which can be either 20a. The tobacco or long cut is then evenly spread along the fold of the apron member so that it is disposed in a uniform manner between the upright members 13 and between the apron and the bend in the cigarette paper designated at 20a. The upright element 13 is then removed from its mounting, tilted toward the front of the apparatus as indicated by the dotted lines in Fig. 3 until it has assumed a substantially horizontal position or in 25 other words is disposed in a plane substantially parallel to that of the base element 10. When the elements are positioned in this manner, pressure is exerted on each end of the upper surface of the element 13 by positioning the thumbs and fingers 30 in the manner illustrated in dotted lines in Fig. 6 of the drawings whereby the tobacco 21 in the apron 11 is forced into the recess generally designated at 10a and while this compressive force by the thumbs is maintained, the element 13 is advanced toward the front of the apparatus thereby imparting a rolling motion to the tobacco mass 21 and the paper 20 which has been forced into substantially the same plane as that of the mat. The undulations in the base member 10 serve to 40 materially facilitate the formation of the cigarette during the rolling operation by assisting in disposing the tobacco and paper in a substantially cylindrical shape. As the tobacco and paper are rolled forward the ends of the paper which were 45 formerly positioned between the recesses 16 and the blocks 15 are turned in by said upright members to form a closed end 26 substantially as shown in Fig. 1. At the completion of the operation the 50 rolled cigarette, ready for gumming, is delivered in the final recess 25 and can then be removed for moistening the gummed portion and sealed in the usual and well known manner.

In the preferred embodiment of the present invention the space between the upper part of the 55 element 13 and the top of the box is provided for the storage of cigarette papers prior to use or, if desirable, this space can be enlarged and utilized for the storage of cigarettes.

It is to be understood that this improvement is 60 capable of extended application and is not confined to the exact showing of the drawings nor to the precise construction described and, therefore, such changes and modifications may be made therein as do not affect the spirit of the invention 65 nor exceed the scope thereof as expressed in the appended claims.

What is claimed as new is:

1. A device of the character described comprising a base having an undulated upper surface, a block removably positionable upon said face, an apron of relatively flexible material, one edge of said apron being substantially fixedly attached to said base, the opposite edge of said apron being substantially fixedly attached to said 75 block, and members abutting against said base,

said members being channeled near the tops thereof, and means attached to said base for covering the device when not in use.

2. A device of the character described comprising a base having an undulated upper surface, a block removably positionable on said base member, an apron of relatively flexible material, one edge of said apron being substantially firmly attached to the undulated surface of said base near a side thereof and between two undulations, the opposite edge of said apron being substantially fixedly attached to said block, and members abutting against said base, said members being channeled on one face near the tops thereof, and means attached to said base for covering the device when not in use. 15

3. A device of the character described comprising a base having an undulated upper surface, a block removably positionable upon one side of said base member in a plane substantially perpendicular to the plane of said base, an apron of relatively flexible material, one edge of said apron being substantially fixedly attached to the undulated surface of said base near a side thereof and between two undulations, the opposite edge of said apron being substantially fixedly attached to said block, and members abutting against said base, said members being channeled on faces thereof near the top, and means attached to said base for covering the device when not in use. 30

4. A device of the character described comprising a base having an undulated upper surface, a block removably positionable upon one side of said base member in a plane substantially perpendicular to the plane of said base, an apron of relatively flexible material, one edge of said apron being substantially fixedly attached to the undulated surface of said base near a side thereof and between two undulations, the opposite edge of said apron being substantially fixedly attached to said block, and members abutting against and disposed substantially perpendicularly to the undulations in said base, said members being channeled on faces nearest the undulated portion of the base, and means attached to said base for covering the device when not in use. 40

5. A device of the character described comprising a base having an undulated upper surface, a block removably positionable upon one side of said base member in a plane substantially perpendicular to the plane of said base, an apron of relatively flexible material, one edge of said apron being substantially firmly attached to the undulated surface of said base near a side thereof and between two undulations, the opposite edge of said apron being substantially fixedly attached to said block, and members abutting against and disposed substantially perpendicularly to the undulations in said base, said members being channeled on faces nearest the undulated portion of the base, said channels being disposed in a plane substantially above the plane including the tops of the undulation in the base, and means attached to said base for covering the device when not in use. 50

6. A device of the character described comprising a base having an undulated upper surface, a block removably positionable upon one side of said base member in a plane substantially perpendicular to the plane of said base, an apron of relatively flexible material, almost equal in width to the width of the undulated portion of said base, one edge of said apron being substantially fixedly attached to the undulated surface of said base near a side thereof and between two 75

undulations, the opposite edge of said apron being substantially fixedly attached to said block, and members abutting against and disposed substantially perpendicularly to the undulations in said base, said members being channeled on faces nearest the undulated portion of the face, said channels being disposed in a plane substantially above the plane including the tops of the undulation in the base, and means attached to said 10 base for covering the device when not in use.

7. A device of the character described comprising a base having an undulated upper portion, a block removably positionable upon one side of said base member in a plane substantially perpendicular to the plane of said base, an apron of relatively flexible material, almost equal in width to the width of the undulated portion of said base, one edge of said apron being substan-

tially firmly attached to the undulated surface of said base near a side thereof and between two undulations, the opposite edge of said apron being substantially fixedly attached to said block whereby the apron is normally disposed upon the 5 tops of the undulations in the base member and against the relatively flat face of the block, thereby assuming a substantially L-shaped configuration, and members abutting against and disposed substantially perpendicularly to the undulations 10 in said base, said members being channeled on faces nearest the undulated portion of the base, said channels being disposed in a plane substantially above the plane including the tops of the undulation in the base, and means attachable to 15 said base for covering the device when not in use.
